UNITED STATES PATENT OFFICE.

CHARLES R. BOHANNON, OF HIGHLAND PARK, KENTUCKY, ASSIGNOR OF ONE-HALF
TO GUY E. WATSON, OF HIGHLAND PARK, KENTUCKY.

INTERNAL-COMBUSTION ENGINE.

Application filed April 21, 1921. Serial No. 463,242.

To all whom it may concern:

Be it known that I, CHARLES R. BOHANNON, a citizen of the United States, residing at Highland Park, in the county of Jefferson 5 and State of Kentucky, have invented certain new and useful Improvements in Internal-Combustion Engines, of which the following is a specification.

This invention relates to internal combustion engines and has special reference to the valve mechanism for controlling the flow of fuel to and from the cylinders of the engine and has for its object the provision of a simple, inexpensive and compact mechanism whereby a single valve will control the charging and exhaust from all the cylinders and will also regulate its own lubrication. Another object of the invention is to provide a structure in which the combustion chambers of all the cylinders will be located in a single casting or member which will also contain the controlling valve, and a further object of the invention is to provide a rotary valve in which a single port 20 will control both the intake and exhaust from any one cylinder. These several objects and other objects which will incidentally appear in the course of the following description are attained in such a mechanism as is illustrated in the accompanying drawings.

In the drawings—

Figure 1 is a vertical longitudinal section through a motor embodying my invention;

Fig. 2 is a transverse section on the line 2—2 of Fig. 1;

Fig. 3 is a similar section taken through one of the cylinders.

The invention is illustrated as applied to a four-cycle engine in which the several cylinders 1, 2, 3, and 4 are formed in a single cylinder block and a single head 5 extends over all the cylinders. The cylinder block 45 is provided at its upper end with lateral flanges 6 and the head is secured upon the block by cap screws or bolts 7 inserted upwardly through the flange into the head as shown in Figs. 2 and 3, a packing or gasket 8 of any suitable material being interposed between the surfaces of the head and the block, as will be readily understood. A series of combustion chambers 9 is formed in the lower side of the head corresponding in number and location with the several

cylinders and adapted to register accurately therewith when the head is placed in position, and it will be noted more particularly upon reference to Fig. 3 that each combustion chamber is expanded laterally somewhat, as shown at 10, whereby a large chamber is produced and, consequently, an ample charge for the successful operation of the motor may be accommodated. The walls of the combustion chamber converge 60 upwardly to a port 11 which admits the inflowing charge and also provides for the escape of the burnt gases, said port 11 being preferably disposed centrally although it may sometimes be found desirable to place 65 it nearer one side of the combustion chamber. The head 5 is also constructed internally with conduits 12 and 13 which are connected, respectively, with the intake and exhaust manifolds and also communicate respectively through ports 14 and 15 with a central longitudinal bore or passage in which the valve 16 is rotatably mounted. The head is, of course, provided with internal walls or partitions 17 which define the 70 sides of the several combustion chambers, as well as the tops thereof, and also furnish the seat or lower support 18 for the valve 16, suitable voids 19 being provided in the head and in the walls of the several cylinders to form a water jacket. Upon referring more particularly to Fig. 2, it will be noted that the horizontal longitudinal wall or inner partition 18 is concave in its upper side 75 so as to provide a suitable bearing for the valve, and between the several ports 11 of adjacent cylinders recesses or cavities 20 are provided in this seat 18 to be filled with felt or similar material; as indicated at 21, to hold a lubricant and apply the same to 80 the surface of the valve in such quantities as will insure easy rotation of the valve without waste of the lubricant. A cap plate 22 is secured on the longitudinal partition or seat 18 and extends over the valve 85 so as to hold the valve to its seat, a gasket 23 being interposed between the seat and the edge portions of the cap to prevent leakage and the cap being secured in place by cap screws or bolts 24, as shown. The 90 said cap plate is provided with recesses or grooves 25 in its side edges and packing 26 is driven into said recesses after the cap 95 is placed in position so that leakage will be prevented. A packing retaining plate 27 100

is placed upon the side flanged portions of the cap and extends over the packing so as to prevent expansion of the same and these plates 27 are held in position by the cap screws or bolts 24. A cover plate 28 is secured upon the head and extends the full length thereof above and in spaced relation to the cap 22, the space between this cover plate and the cap constituting a portion of the water-circulating system. At any convenient point of the cover plate 28, a pipe or hose 29 may be secured so as to establish communication with the radiator.

The valve 16 consists of a bar or rod of circular cross section having a trunnion 30 at one end rotatably fitted in the adjacent end of the head and equipped with a reduced stud or lug 31 whereby it may be coupled with the magneto. At the opposite end of the valve is a trunnion 32 upon which the timing gear 33 is secured and this gear and the trunnion carrying it are housed within the gear casing 34. An adjusting screw 35 is mounted in the adjacent outer wall of the gear casing and has its inner end engaged in a seat 36 formed in the end of the trunnion 32 whereby the valve may be readily adjusted in an obvious manner, a lock nut 37 being provided to retain the screw in an adjusted position. The lubricant is supplied to the valve chamber and the valve by a pump (not shown) in the manner now generally employed and is delivered in position to be received by an annular groove 38 formed in the surface of the valve at the end thereof adjacent the trunnion 30, packing 39 of felt or similar material being interposed between said end of the valve and the adjacent end of the head and below the valve so as to prevent excessive flow of the lubricant. A radial port or passage 40 leads from one point of the groove 38 through the valve into the central bore 41 thereof and the lubricant flows through the said port into said bore and then longitudinally through the valve, other radial ports 42 being provided at intervals in the valve to permit some of the lubricant to flow to the several pads 21 in the lubricant-containing recesses 20 between the several cylinders. I thus provide for thorough lubrication of the valve and also guard against flow of the lubricant into the cylinders. The bore 41, as shown clearly in Fig. 1, is closed at its receiving end, except for the adjacent port 40, but at the opposite end of the valve the said bore is open and communicates directly with a passage 43 in the end of the adjusting screw 35 whereby the excess lubricant may return through the gear case to the crank case of the motor and thence through the lubricating system, as will be readily understood.

In the circular surface of the valve, I form a plurality of ports or recesses 44

which correspond in number to the cylinders of the motor and are spaced about the valve both longitudinally and annularly so that the admission to and exhaust from the several cylinders will occur in the proper sequence. Each recess, channel, or port 44 is preferably equal in length to the length of the port 11 with which it cooperates and in width covers about one-third of the circumference of the valve, the intake and exhaust ports 14 and 15 being disposed at the sides of the valve at diametrically opposite points and slightly below the axis thereof, as shown clearly in Fig. 3. The valve rotates at about one-half the speed of the crank shaft and in the direction indicated by the arrow in Fig. 3 which shows the valve in the position assumed just after the exhaust from the cylinder has been completed and just prior to the admission of another charge. It will be readily noted that in this position of the valve, the port 44 extends over the port 11 of the combustion chamber and the unmutilated portion of the surface of the valve extends over both ports 14 and 15. As the valve rotates in the direction indicated by the arrow thereon in Fig. 3, the forward longitudinal wall of the port 44 will clear the lower wall of the port 14 and fuel will then begin to flow through the port 44 and the port 11 into the combustion chamber and the cylinder. This flow will continue until the rear longitudinal wall of the port 44 clears the port 11, whereupon the continued flow will be cut-off and the unmutilated portion of the surface of the valve will extend over the port 11 so that said port will be closed. The piston of the engine will then make its compression stroke and also its power stroke, while the unmutilated portion of the valve covers the port 11 and the port 14, the charge being fired in the usual manner by a spark plug which may be located at any convenient point of the combustion chamber. The spark plug may be of any well-known type operating in the usual manner and as it forms no part of my present invention I have deemed its illustration unnecessary. As the engine piston reaches the end of its power stroke and begins its return movement or exhaust stroke, the advance longitudinal wall of the port 44 will begin to move over the port 11 so that communication will be established between the said port and the exhaust port 15 and the exhaust gases will then be permitted to escape in an obvious manner, the completion of the exhaust stroke bringing the valve back to the position shown in Fig. 3.

From the foregoing description, taken in connection with the accompanying drawings, it will be seen that I have provided a very simple, compact and easily operated valve, whereby a single valve will control the ad-

mission to and exhaust from all the cylinders of the motor and it will, of course, be understood that while I have shown a motor containing four cylinders, the invention is applicable without material change in structure to a motor having any number of cylinders. It is to be particularly noted that my invention provides a large combustion chamber, and the combustion chambers and the valve mechanism are all contained within a single casing or casting so that the number of parts are reduced and the cost of construction thereby lessened over the structures heretofore employed. The simplicity of my device prolongs the life of the same and also reduces the cost of maintenance and by reason of its ease of operation more of the power generated is utilized for driving the machinery to which the motor is connected than has been possible with other constructions.

Having thus described the invention, what is claimed as new is:

1. The combination of a cylinder block containing a cylinder, a head detachably secured upon said block and containing partitions defining a combustion chamber communicating with said cylinder, the head being provided with a port and a seat in the partitions at the upper end of the combustion chamber and with intake and exhaust ports at opposite sides of the combustion chamber, a rotary valve mounted longitudinally in the head and resting in said seat and provided with a single recess in its surface adapted to establish communication between the combustion chamber and either the intake or the exhaust port, and a cap plate secured longitudinally on the head across the intake and exhaust ports and resting upon the valve to hold the same to its seat, said cap plate being co-terminous with the head and there being a longitudinal opening through the top of the head to permit removal of said cap plate.

2. The combination of a cylinder block containing a cylinder, a head detachably secured upon the block and containing partitions defining a combustion chamber and water-circulating passages and having intake and exhaust ports formed in said partitions, a rotary valve disposed longitudinally in the head between the intake and exhaust ports and constructed to establish communication between the combustion chamber and either the intake or the exhaust port, a cap plate fitting over said valve to hold the same to its seat and secured upon some of the partitions in the head and co-terminous with the head, and a cover plate secured upon the head above and in spaced relation to the said cap plate, the space between the

cover plate and the cap plate being open and forming a part of the water-circulating system and permitting withdrawal of the cap plate when the cover plate is removed.

3. The combination of a cylinder block, a head detachably secured upon the block and containing combustion chambers communicating with the respective cylinders in the cylinder block and having partitions defining said combustion chambers, all said partitions being provided in their upper sides with recesses between the combustion chambers, absorbent fillers in said recesses, a rotary valve mounted longitudinally in the head and resting upon the said partitions and provided with radial ports arranged to communicate with the respective recesses in the said partitions, a longitudinal bore in the valve communicating with the said several radial ports, and means for supplying a lubricant to one end of said bore.

4. The combination of a cylinder block containing cylinders, a head secured upon the block and containing partitions defining combustion chambers communicating with the respective cylinders, said partitions being provided with recesses in their upper surfaces, a rotary valve mounted longitudinally in the head and extending over the said recesses and the several combustion chambers, said valve being provided at one end with a trunnion journaled in the adjacent end of the head and at its opposite end with a trunnion having a socket in its extremity, the valve being provided with an axial bore closed at the first-mentioned end thereof and opening through the second-mentioned trunnion and with radial ports arranged to establish communication between said bore and the several recesses, and an adjusting screw engaging the socketed extremity of the second-mentioned trunnion and provided with a passage establishing a discharge from the adjacent end of the bore in the valve.

5. In an internal combustion engine, the combination of a cylinder block containing cylinders, a head detachably secured upon the cylinder block and constructed with combustion chambers communicating with the respective cylinders, a rotary valve seated longitudinally in the head and having an axial bore closed at one end, a radial port leading into said bore at the closed end of the valve and radial ports leading from the bore to the valve seat, and an adjusting screw engaging and supporting the valve at the open end of the bore and provided with a passage establishing a discharge from the bore.

In testimony whereof I affix my signature.
CHARLES R. BOHANNON. [L. S.]
